UNITED STATES PATENT OFFICE

122,269

DESIGN FOR A HOLLOW GLASS
BUILDING BLOCK

Roy C. Kendall, Toledo, Ohio, assignor to Owens-
Illinois Glass Company, Toledo, Ohio, a corpo-
ration of Ohio

Application July 18, 1940, Serial No. 93,772

Term of patent 14 years

To all whom it may concern:

Be it known that I, Roy C. Kendall, a citizen of the United States, residing at Toledo, in the county of Lucas and State of Ohio, have invented a new, original, and ornamental Design for a Hollow Glass Building Block, of which the following is a specification, reference being had to the accompanying drawing, forming a part thereof.

In the drawing:

Fig. 1 is a perspective view of a hollow glass

building block showing my new design. A portion of the block is broken away in this view to show the ribbed and stippled interior which affect the exterior appearance of the unit.

Fig. 2 is a sectional view taken along the line 2—2 of Fig. 1 showing the interior and exterior surface contour.

I claim:

The ornamental design for a hollow glass building block, substantially as shown and described.

ROY C. KENDALL.
